UNITED STATES PATENT OFFICE.

BRYAN P. JOYCE, OF DAVENPORT, IOWA.

CYLINDER HEAD AND PACKING.

Application filed July 18, 1927. Serial No. 206,567.

The subject matter of the present invention is a packing and pertains more particularly to the construction and assembly of a packing to seal cylinder heads, especially the heads of high pressure cylinders.

Among the objects of this invention are to so assemble the packing as to obtain a maximum cylinder volume for a given length of cylinder; to reinforce the cylinder at the point where the head is attached thereto; to so construct a device of this kind that pressure will tend to hold the parts in closer relation, instead of causing separation thereof; to provide an improved means for forming a tight joint between the cylinder and its head; to provide means for locking the parts in adjusted relation; and such further objects, advantages and capabilities as will hereafter appear and as are inherent in the construction disclosed. My invention further resides in the combination, construction and arrangement of parts illustrated in the accompanying drawing and, while I have shown therein what is now considered the preferred embodiment of this invention, I desire it understood that the same is to be construed as illustrative only and not to be interpreted in a limiting sense.

The packing disclosed in my Patent No. 1,635,482, issued July 12, 1927, or any other comparable, suitable packing may be used in this invention. It has been the practice to assemble this type of packing as disclosed at 9 in my Patent No. 1,607,350, issued November 16, 1926. Under pressure, this packing may be considered a semi-fluid and it exerts greater pressure upon the cylinder wall than the pressure of the fluid within the cylinder.

According to present practice, the cylinder wall is made thinner at this point of greatest pressure in order to provide a shoulder, as disclosed at 5' in Patent No. 1,607,350, against which shoulder the cylinder head is seated. In small cylinders or in those utilizing a low pressure, this is unimportant, but in large cylinders with high pressures where the full strength of the cylinder is necessary, it is important, for it necessitates upsetting the end of the cylinder or machining the cylinder, in order to obtain the requisite cylinder thickness at this point of greatest stress. The present invention permits the use of tubing of uniform wall thickness. The present invention is designed to obviate the foregoing difficulties, reducing the cost of manufacture, and producing a superior article.

One embodiment of my invention is illustrated, by way of example, in the accompanying drawing, in which Fig. 1 is a fragmentary plan view of a cylinder head having my invention applied thereto and Fig. 2 is a cross section substantially along the plane indicated by the line 2-2, Fig. 1.

Referring more in detail to the annexed drawing, the cylinder 3 has a head 4 provided with a radially outwardly extending flange 10 which cooperates with the packing member consisting of a lead ring 5 between copper rings 6. Other suitable packing rings may be used for the same purpose. The head securing ring 7 has screw-threaded connection with the end of cylinder 3 and is provided with an inwardly extending flange overlapping the end of the cylinder and extending into contact with the outer cylindrical wall of the head. Extending longitudinally of the cylinder and into the end thereof, as shown at 8, is a flange which serves as a seat for the packing ring. This latter is compressed between the flanges 8 and 10. The outer end of the head 4 is screw-threaded for the reception of the ring 9 by means of which the flanges 8 and 10 are drawn toward each other to compress the packing ring. The edge of this ring may be provided with notches 11, as shown in Fig. 1, to permit the insertion of a locking screw 12 which will prevent the ring 9 from working loose on the head 4. This screw 12 may also serve to lock the ring 7 relatively to the cylinder 3 whereby to prevent the same from backing off from the cylinder, thus permitting the head to be blown out. The cylinder wall may be slightly beveled, if desired, as shown at 13, in order to facilitate the assembly of the head and cylinder.

In assembling the parts, the head, packing and rings 7 and 9, are loosely assembled and then the ring 7 is put upon the end of the cylinder and screwed down as far as it will go. The ring 9 is then tightened until the packing is compressed and tightly engages both the cylinder and the outer cylindrical wall of the head. The screw 12 is then inserted through one of the notches 11 into the hole provided therefor in the flange of the ring 7 and is screwed in until it locks the entire assembly in place.

In the construction disclosed in my Patent No. 1,607,350, the pressure of the fluid in the cylinder had a tendency to expand the cyl-

inder, reducing the stress of the connection between the cylinder wall and the ring 10, thus necessitating an extra length of screw-threading at this point. In my present construction, expansion of the cylinder increases, rather than diminishes, the pressure of the contact between the threads of the cylinder 3 and the ring 7, thus decreasing the necessary length of thread. As the threads of the ring 7 are a close fit upon the threads of the cylinder 3, the strength of the assembly at the packing is the sum of the cylinder strength and the strength of the ring 7. From this it will be seen that the addition of the cylinder head assembly increases the cylinder strength at this point instead of diminishing it as in my prior patent referred to above. It will also be seen from the present disclosure that the present construction gives a greater internal volume for a given length of cylinder than my prior construction, with the result that there is a saving in weight and material for a given volume of cylinder.

While I have shown and described a certain specific embodiment of my invention, it is of course understood that the specific description of structure set forth above may be departed from without departing from the spirit of my invention as set forth in this specification and the appended claims.

Having now described my invention, I claim:

1. In a cylinder head packing assembly, a cylinder, separable means to reinforce the cylinder at the packing and to seat the packing, a packing ring cooperating therewith, a cylinder head associated with the end of the cylinder, and means to secure the head in position, said head having a projecting part engaging the packing ring and adapted to transmit pressure over a portion of its area to the packing.

2. In a structure of the character indicated, a cylinder having threads formed upon the outer circumference thereof to receive a ring, a ring engaging said threads and having a portion extending inwardly into the cylinder to seat a packing, a packing ring resting against the inwardly extending portion, a cylinder head closing the end of the cylinder, and means to secure the head in position, said head having a projecting part engaging the packing ring and said projecting part being adapted to transmit pressure over the whole of its area to the packing.

3. In a structure of the character indicated, a cylinder externally screw-threaded at one end, an internally threaded ring mounted upon the screw-threaded end of the cylinder, said ring having an inwardly projecting flange serving as a support for a packing ring, a cylinder head within the ring and having a flange extending outward

ly into engagement with the cylinder, and a packing ring located between the flanges to seal the opening between the head and cylinder.

4. In a structure of the character indicated, a cylinder externally screw-threaded at one end, an internally threaded ring mounted upon the screw-threaded end of the cylinder, said ring having an inwardly projecting flange serving as a support for a packing ring, a cylinder head within the ring and having a flange extending outwardly into engagement with the cylinder, and a metallic packing ring located between the cylinder, its head, and the flanges, to seal the opening between the head and cylinder.

5. A structure of the character indicated, comprising a cylinder, a securing ring threaded over the end of the cylinder and having an inwardly extending flange projecting within the cylinder to seat a packing ring, a cylinder head within the ring flange and having a flange projecting radially into engagement with the cylinder, a packing ring between said flanges, and means to draw the flanges toward each other to compress the packing.

6. A structure of the character indicated, comprising a cylinder, a securing ring threaded over the end of the cylinder and having an inwardly extending flange projecting within the cylinder to seat a packing ring, a cylinder head within the ring flange and having a flange projecting radially into engagement with the cylinder, said head projecting outwardly beyond the ring flange, a packing ring between said flanges, and screw-threaded means cooperating with the projecting portion of the head to cause the flanges to move toward each other and compress the packing.

7. In a structure of the character indicated, a high pressure cylinder externally screw-threaded at one end, a cylinder head located within the cylinder and contacting with the inner wall thereof, said head being reduced in diameter between its ends, a packing ring in the reduced portion of the head, a securing ring surrounding said head and the end of the cylinder and being secured to the cylinder by the screw threads, said ring forming a seat for the packing against which the packing may be pressed by the head, and means to draw the head against the packing and cause the latter to be compressed between the head and the securing ring.

8. In a structure of the character indicated, an externally screw-threaded high pressure cylinder, a ring connected to the cylinder by the screw threading, said ring having a part extending into the cylinder to form supporting means for a cylinder head, a flanged cylinder head within the end of the cylinder and having a portion thereof projecting beyond the end of the cylinder.

inder and the ring, said projecting portion being screw-threaded for the reception of a retaining member, a packing in the space between the head and the ring, said packing being capable of being compressed upon relative movement between said ring and head, a second ring mounted upon the end of the head and secured thereto by the screw threading, said second ring serving to move the head relatively to the first ring and thereby compress the packing, and means to prevent relative turning movement of a ring with relation to the part to which it is secured.

In witness whereof, I hereunto subscribe my name to this specification.

BRYAN P. JOYCE.
